BLANK FEEDING MECHANISM

Eugene B. Berkowitz, Kansas City, Mo.

Application August 13, 1934, Serial No. 739,600

13 Claims.

(Cl. 271—1)

This invention relates to blank feeding mechanisms and more particularly to those of that character for feeding blanks into an envelope forming machine, the present invention being directed to improvements in a similar feeding device disclosed in United States Letters Patent No. 1,646,230, issued to me on October 18, 1927.

Feeding devices of the type illustrated in said Letters Patent operate successfully in delivering plain blanks, but when the blanks carry printed matter on the faces thereof, or are of the open window type, the feeding mechanism tends to smear the printing, or wrinkle the blanks so that the envelopes produced therefrom do not have the desired appearance.

It is, therefore, the principal object of the present invention to effect feed of the blanks so that they are not defaced by the feeding mechanism and to relieve the pressure of the stack upon the lowermost blank while it is being separated therefrom and delivered into the envelope forming machine.

In accomplishing these and other objects of the invention, as hereinafter pointed out, I have provided improved details of structure, the preferred form of which is illustrated in the accompanying drawings, wherein:

Fig. 1 is a plan view of a portion of an envelope forming machine equipped with the blank feeding mechanism embodying the features of the present invention.

Fig. 2 is a longitudinal vertical section on the line 2—2 of Fig. 1.

Fig. 3 is a side elevation, particularly illustrating the driving mechanism for the blank feeding means.

Fig. 4 is a detail perspective view of a stack of blanks shown in relation to the supporting disks and the vacuum nozzle in engaging relation with the lowermost blank in the stack to permit entrance of the separator for supporting the weight of the remaining blanks in the stack from the blank being removed.

Fig. 5 is a similar view showing the disks in the act of separating the blank being withdrawn from the stack.

Fig. 6 is a similar view showing the disks moving into position for again supporting the stack while the separator member is moving out of supporting relation with the stack and the nozzle is moving into position for engaging the next lowermost blank in the stack.

Fig. 7 is an enlarged detail section through one of the disks particularly illustrating the driving gear therefor and the rollers on the stack

supporting portion of the disk which prevent smearing of printing on the face of the blanks.

Fig. 8 is an enlarged perspective view of one of the disks as viewed from above or the stack supporting side thereof.

Fig. 9 is a similar perspective view of one of the disks as viewed from beneath.

Referring more in detail to the drawings:

1 and 2 designate the side frames of an envelope forming machine of the type wherein individual blanks are successively fed into the machine to be acted upon by a forming mechanism to convert the blanks into finished envelopes. Connecting the side frames 1 and 2 at the feeding end of the machine are spaced transverse bars 3, 4, 5 and 6 arranged at an inclined angle as shown in Figs. 2 and 3 to support a stack of blanks in angular relation to the blank forwarding mechanism of the envelope machine, as indicated by the pressure rollers 7 and conveyor belt 8.

Fixed to the lowermost bar 6 at a point midway between the side frames 1 and 2 is a plate 9 extending upwardly toward the conveyor belt 8 and having its upper end 10 terminating in substantially the horizontal plane of the blank forwarding means. The end 10 of the plate 9 is supported from the bar 5 by means of a stud 11 fixed to the under side thereof and extending through an opening 12 in the bar. Threaded on the stud 11 and engaging opposite sides of the bar are nuts 13 and 14 whereby the end of the plate is adjustably positioned relatively to a stack of blanks 15 that is, at times, supported upon the upper run 16 of belts 17 and 18, which operate over the plate 9, the belts 17 and 18 being spaced apart and running over pairs of pulleys 19 and 20 that are carried on shafts 21 and 22 having their ends rotatably mounted in the side frames 1 and 2.

The shaft 22 carrying the pulleys 20 is rotated by a gear 23 thereon meshing with a gear 24 that is rotatably mounted on one of a pair of spaced stub shafts 25 extending inwardly from the side frames 1 and 2.

The stub shafts are driven by sprockets 26 on a counter-shaft 27 by a chain 28 operating over the sprockets 26 and aligning sprockets 29 on the stub shafts 25, the ends of the counter shaft being rotatably mounted in the side frames 1 and 2 at a point below the conveyor shaft 22.

The counter-shaft 27 is driven by a gear 30 thereon which meshes with a gear 31 keyed to an operating shaft 32 of the envelope machine so that the countershaft is driven in timed relation

with the blank forwarding means of the envelope machine which includes the conveyor belt 18 and the forwarding rollers 7.

The stack of envelope blanks 15 is supported in position over the belts 17 and 18 by standards 33 and 34 which are adjustably carried on the bar 6 by means of arms 35 and 36 fixed to the lower ends of the standards and which have slots 37 for passing the bolt 38 by which the arms 10 are secured to the cross bar 6. The arms 35 and 36 are adapted to move radially on the bolts 38 and slidably thereon to position the standards 33 so that they will lie within the angle of the end and sealing flaps of the envelope, as indicated at 39 and 40, respectively.

Extending inwardly of the side frames 1 and 2 adjacent the opposite side of the end flaps are inwardly extending rods 41 and 42 carrying heads 43 and 44 for mounting slotted arms 45 and 46 having depending pins 47 and 48 engaging in the angle between the end flaps and the opposite sealing flap 49 similarly to the standards 33 and 34.

The stack of envelope blanks is thus supported against shifting movement relatively to the belts 17 and 18, but the ends of the rods 47 and 48, terminating adjacent the bottom of the stack, permit the lowermost blank to be withdrawn as hereinafter described.

In order to intermittently support the stack out of contact with the belts 17 and 18, I provide a cross shaft 50 having its ends rotatably mounted in the side frames and carrying arms 51 and 52 provided with rollers 53 and 54 on the terminal ends thereof which are adapted to engage against the bottom of the stack so that when the shaft is rocked in an anti-clockwise direction, Fig. 2, the rollers are caused to engage the bottom of the stack to lift the stack from contact with the belts. In order to rock the shaft, the end thereof that is mounted in the frame 2 carries a rocker arm 55 that is connected with a lever 56 slidably mounted on the side frame and carrying a cam follower 57 engaging against a cam 58 on the end of the counter shaft 27, the cam follower being retained against the cam by a spring 59 having one end fixed to a pin 60 on the rock lever and its other end to the frame 2, as best illustrated in Fig. 3.

Cooperating with the rollers 53 and 54 in supporting the stack are laterally spaced disks 61 and 62 fixed to the lower ends of shafts 63 and 64 that are rotatably mounted in bearing brackets 65 and 66 adjustably secured to the cross bar 4 by bolts 67 projecting through the brackets and through slots 68 of the bar 4 whereby the brackets carrying the disks may be moved to and from the conveyor belts 17 and 18 for adjustment when blanks of different widths are run through the machine. Also carried by the brackets 65 and 66 are the inner ends of horizontally arranged shafts 69 and 70 having bevelled gears 71 and 72 thereon meshing with bevelled gears 73 and 74 on the disk shafts 63 and 64. The outer ends of the shafts 69 and 70 are rotatably mounted in bearings 75 on the side frames 1 and 2 and carry gears 76 that are driven from gears 77 fixed to the outer ends of the shafts 25 through idler gears 78 mounted on stub shaft 79, as best shown in Fig. 3.

It is thus apparent that the disks are rotatably mounted for movement under the stack of blanks in timed relation with swinging movement of the

rollers 53 and 54 since they are both operated from the common counter shaft 27.

The disks are best illustrated in Figs. 8 and 9 and include flat web portions 80 fixed to the respective disk shafts by means of hubs 81 having integral flanges 82 that are secured to the web portion by screws 83.

The upper face of the web portions of the disks include segmental circular tracks 84 having rounded ends 85 and 86 spaced apart to form 10 throats 87 through which the bottom flap of the envelope blanks are drawn when they are removed from the stack. The body portion 80 of the disk is also cut away at the throats, as at 88, to provide greater clearance for the flaps of the 15 envelope blanks.

The outer periphery of the track 84 is provided with a depending annular flange 89 to stiffen the disks and to provide guards for covering the lower portion of a series of spaced rollers 90 that are 20 rotatably mounted within slotted openings 91 of the disks to provide rolling support against the bottom of the stack when the stack has been lowered by the rollers 53 and 54 to contact the lowermost blank with the conveyor belts 17 and 25 18.

The rollers 90 are rotatably mounted in the slots 91 on shafts 92 having ends 93 that are secured to the under side of the disks 61 and 62, as shown in Fig. 9.

The opposite end 85 of the track is reduced in thickness to form an entering edge for readily permitting its passage over the lower blank to separate it from the other blanks when the stack is raised from contact with the conveyor belts, 35 as later described.

To support the front of the stack of blanks while the rear of the stack is being supported by the rollers, I provide an arm 94 having a pointed separator 95 on its lower end which is adapted to 40 be projected under the stack when the arm is moved toward the stack, as shown in Fig. 2.

The arm 94 is carried on a rod 96 that is slidably in a base 97 carried on the bar 4 and having a slot 98 to pass a guide pin 99 that is connected with a rocking lever 100 fixed on a shaft 101 which is rotatably mounted in bearing brackets 102 and 103 carried by the bar 4. The shaft 101 carries an arm 104 having a roller 105 engaging a cam 106 on the shaft 70 whereby the shaft 101 is rocked to reciprocate the arm 94 to and from engagement with the stack.

Also carried by the base 97 is an upwardly extending bracket arm 107 to which is pivoted a depending lever 108 that is adapted to be held 55 in engagement with the stack by means of a set screw 109 which is threaded through the bracket arm 107 and engages against the rear of the lever arm. The lever arm is retained against the end of the set screw by a coiled spring 110 having one 60 end fixed to the lever arm and its opposite end extending through an opening 111 in the bracket arm and secured to a hook 112 projecting laterally from the opposite side of the bracket arm.

The lower portion of the lever arm which engages the stack is provided with teeth or prongs 113 for engagingly supporting the upper blanks in the stack to relieve pressure thereof on the lower blanks.

A vacuum nozzle 114 is provided for engaging 70 the lower blank in the stack to bend the flap downwardly through the throats formed in the disks at the time the stack supporting portions of the disks are moving under the stack as now to be described.

Extending across the side frames 1 and 2 at a point below the cross bar 3 is a rock shaft 115 carrying the vacuum nozzle 114 which is adapted to be swung to and from engagement with the apex of the bottom flap of the lower blank to carry the flap into position to be engaged by drawing in fingers 116 that are fixed to cranks 117 eccentrically mounted on the ends of the stub shafts. When engaged by the fingers 116, the blank is moved into driving contact with the belts 17 and 18 at the point where they move across the pulleys 20.

In order to permit easy entrance of the separator point of the arm 94 between the lowermost blank and the blanks remaining in the stack, the vacuum nozzle is provided with a concavity into which the flap of the lowermost blank is drawn which leaves an opening so that the separator can enter therethrough to engage the bottom of the stack and support it while the nozzle is carrying the lowest blank into position to be engaged by the pins.

The vacuum nozzle shaft is rocked by a cam 118 fixed to the outer end of the counter shaft 27 and which engages a roller 119 on a connecting link 120 having its upper end fixed to a laterally extending arm 121 on the end of the shaft 115, the lower end of the arm 120 being provided with a yoke 122 which engages over the shaft 27 to form a guide. The roller 119 is retained in contact with the cam 118 by means of a spring having one end fixed to the lever arm 121 and its opposite end to a pin extending from the side frame 2, as best shown in Fig. 3.

In operating a machine constructed and assembled as described, a stack of blanks is supported over the belts 17 and 18 so that the bottom flaps thereof lie directly in the path of movement of the vacuum nozzle.

When the machine is started, the disks rotate under the stack to alternately support the stack and to effect separation of the blank being moved by the nozzle.

The machine is so timed that while the stack supporting portion of the disks which carry the rollers is in contact with the under side of the stack, the nozzle is moved into engaging position with the lowermost blank in the stack.

When the vacuum nozzle engages the blank, the apex of the bottom flap is drawn within the concavity of the nozzle to permit ready engagement of the separator point of the arm 94 to support the other blanks in the stack while the nozzle is drawing the flap of the bottom blank in the direction of the conveyor belts 17 and 18.

When the last roller 90 is moving under the stack, the vacuum nozzle begins to move downwardly to carry the bottom flap of the lower blank through the throat portion of the disks. Continued rotation of the disks carry the ends 85 thereof into separating relation with the stack. At this time the cam 59 actuates the lever arm 55 to rock the shaft 50 to move the rollers 53 and 54 upwardly into supporting relation with the stack 65 and raise it out of contact with the separating portion of the disks.

By this time the drawing-in fingers 116 have engaged the flap which has been withdrawn by the nozzle to remove the blank from the nozzle and carry it into contact with the belts 17 and 18 at the point where the belts move over the pulleys 20. During this movement of the blank being withdrawn, the stack supporting portion of the disks are again moving into supporting relation with the bottom of the stack and the

vacuum nozzle has returned to engage the next blank.

As soon as the disks are in supporting relation with the bottom of the stack, the arm 94 carrying the pointed separator has been moved out of engagement with the stack to effect engagement of the lowermost blank remaining in the stack by the nozzle. Simultaneously, the rollers 53 and 54 have been lowered out of contact with the bottom of the stack to permit the rear 10 portion with the partly withdrawn blank to contact with the conveyor belts 17 and 18. The withdrawn blank is then moved by the conveyor belts to the blank-forming mechanism of the envelope machine (not shown).

The remaining blanks in the stack are fed consecutively into the blank forwarding means in the same manner as the blank just described.

From the foregoing it is apparent that I have provided a feeding arrangement whereby the separating and stack supporting disks do not move in wiping contact with the bottom of the stack because the rollers therein engage the stack and roll over the printed surface thereof so that they do not smear the ink or wrinkle the blanks, particularly if the blanks being run through the machine are provided with window openings.

What I claim and desire to secure by Letters Patents:

1. In a device of the character described, means for retaining a stack of blanks, means for intermittently supporting the stack of blanks in said retaining means, means for supporting the stack during the intervals between support by said first named means, and anti-friction members on sail first named supporting means for contacting the stack to prevent smearing of printed matter on the blanks.

2. In a device of the character described, means for retaining a stack of blanks, rotary means for intermittently supporting the stack of blanks in said retaining means, means movable to and from the stack for supporting the stack during the intervals between support by said rotary means, and rollers on said rotary means for contacting the stack to prevent smearing of printed matter on the blanks.

3. In a device of the character described, guide means for retaining a stack of blanks, a rotary member mounted under the stack having a stack supporting portion and a separating portion to alternately support the stack and separate the lowermost blank in the stack, means independent of said supporting portion for supporting the stack while the lowermost blank is being separated by said separating portion, and means on said supporting portion for rolling contact with the stack.

4. In a device of the character described, guide means for a stack of blanks, rotary members mounted under the stack having stack supporting portions and separating portions to alternately support the stack and separate the lowermost blank in the stack, rollers on said supporting portions for rolling contact with the stack, and a second supporting means operating in synchronism with the rotary members while said separating portions are effective.

5. In a device of the character described, guide means for retaining a stack of blanks, rotary members mounted under the stack having stack supporting portions and separating portions to alternately support the stack and separate the lowermost blanks in the stack, rollers on said supporting portions for rolling contact with the stack,

- means for engaging a portion of the lowermost blank to carry said portion of the blank away from the stack to permit entrance of said separating portions therebetween, and supplementary means for supporting the stack while supporting portions of the rotary members are out of supporting relation with the stack.
6. In a device of the character described, guide means for retaining a stack of blanks, rotary members mounted under the stack having stack supporting portions and separating portions to alternately support the stack and separate the lowermost blanks in the stack, rollers on said supporting portions for rolling contact with the stack, a suction nozzle for engaging a portion of the lowermost blank, means movably supporting the nozzle to carry said portion of the blank away from the stack to permit entrance of said separating portions of the rotary members therebetween, supplementary means for supporting the stack while supporting portions of the rotary members are out of supporting relation with the stack, and means movable in synchronism with the suction nozzle to support said portions of the blanks remaining in the stack.
- 10 7. In a device of the character described, a supporting frame, guide means on the frame for retaining a stack of blanks, primary and secondary means for alternately supporting the blanks in the guide means, blank separating means cooperating with one of the supporting means, means for engaging the lower blank in the stack to permit entrance of said separating means, means carried by the frame for removing the separated blank, and means for alternately rendering said supporting means effective in supporting the stack.
- 15 8. In a device of the character described, a supporting frame, guide means on the frame for retaining a stack of blanks, primary and secondary means for supporting the blanks in the guide means, means for successively removing the lowermost blank from the stack, and means operating in synchronism with said removing means for alternately rendering said supporting means effective in supporting the stack.
- 20 9. In a device of the character described, guide means for retaining a stack of blanks, rotary members mounted under the stack having stack supporting portions and separating portions to alternately support the stack and separate the lowermost blanks in the stack, a suction nozzle for engaging a portion of the lowermost blank, means movably supporting the nozzle to carry said portion of the blank away from the stack to permit entrance of said separating portions of the rotary members therebetween, supplementary means for supporting the stack while supporting portions of the rotary members are out of supporting relation with the stack, and means movable in synchronism with the suction nozzle to support said portions of the blanks remaining in the stack.
- 25 10. In a device of the character described, guide means for retaining a stack of blanks, rotary members mounted under the stack having stack supporting portions and separating portions to alternately support the stack and separate the lowermost blanks in the stack, rollers on said supporting portions for rolling contact with the stack, a suction nozzle for engaging a portion of the lowermost blank, means movably supporting the nozzle to carry said portion of the blank away from the stack to permit entrance of said separating portions of the rotary members therebetween, supplementary means for supporting the stack while supporting portions of the rotary members are out of supporting relation with the stack, and means movable in synchronism with the suction nozzle to support said portions of the blanks remaining in the stack.
- 30 11. In a device of the character described, guide means for retaining a stack of blanks, rotary members mounted under the stack to alternately support the stack, rollers on said rotary members for rolling contact with the stack, a suction nozzle for engaging a portion of the lowermost blank, means movably supporting the nozzle to carry said portion of the blank away from the stack, supplementary means for supporting the stack while supporting rotary members are out of supporting relation with the stack, and means cooperating with the nozzle to complete the removal of the blank.
- 35 12. In a device of the character described, a supporting frame, means on the frame for retaining a stack of blanks, primary means for intermittently supporting the stack of blanks in said retaining means, means for actuating said primary supporting means, a shaft mounted in said frame, arms on said shaft, rollers on the shaft and adapted to engage the stack, and means for rocking the shaft to move said rollers to and from the stack in timed relation with said primary supporting means whereby the stack is supported on said rollers during the intervals between support by said primary supporting means.
- 40 13. In a device of the character described, a supporting frame, means on the frame for retaining a stack of blanks, primary means for intermittently supporting the stack of blanks in said retaining means, means for actuating said primary supporting means, a shaft mounted in said frame, arms on said shaft, rollers on the shaft and adapted to engage the stack, means for rocking the shaft to move said rollers to and from the stack in timed relation with said primary supporting means whereby the stack is supported on said rollers during the intervals between support by said primary supporting means, and anti-friction members on said primary supporting means for contacting the stack to prevent smearing of printed matter on the blanks when the stack is supported by said primary supporting means.
